FOLLOWER CONSTRUCTION FOR FILING
DRAWERS

Frederick L. G. Straubel, Green Bay, Wis., assignor of one-eighth to O. C. Straubel, Green Bay, Wis., and two-eighths to C. W. Straubel, Youngstown, Ohio

Application September 5, 1933, Serial No. 688,226

9 Claims. (Cl. 129—28)

This invention relates to improvements in drawers for filing cabinets and the like, and is a continuation in part of my application, Serial No. 670,180, filed May 9, 1933. The structure shown 5 in Fig. 1 of this case also appears in the above mentioned application.

A primary object of the invention is to provide a novel follower construction and arrangement which cooperates with the compressor in such a 10 way that when the drawer is filled to capacity, the drawer contents will not be forced rearwardly above the back edge of the drawer so as to prevent the drawer fully closing in the cabinet. In other words, the construction provides a follower 15 adapted to assume a more nearly vertical position as it approaches the back of the drawer, thereby forming a surface inwardly of the drawer end, and against which the drawer contents rest.

A further object of the invention is to provide 20 simple, practical and reliable means for mounting and manipulating the follower in the drawer.

With the above and other objects in view which 25 will more readily appear as the nature of the invention is better understood, the invention consists in the novel features of construction, combination and arrangement of parts, hereinafter more fully described, illustrated in the accompanying drawings and defined in the appended 30 claims.

30 A preferred and practical embodiment of the invention is shown in the accompanying drawings, in which:—

Figure 1 is a vertical cross-sectional view of 35 a drawer embodying the present improvements.

Figure 2 is a detail view of the follower showing a spring connected to the carrier and the support for the follower plate.

Figure 3 is a transverse vertical sectional view illustrating the manner of mounting the 40 space regulating follower in the drawer.

Referring to the drawings, the drawer is designated generally as A, and as usual comprises the side walls 1, rear wall 3 and bottom 4. At the front of the drawer there is provided a tilting 45 front or drawer head designated generally as B carrying at its inner face the compressor device C. Slidably mounted within the contents receiving space of the drawer is a novel follower construction designated generally as D.

With reference to the follower D, it will be observed that the same includes a follower plate 33 hinged as at 34 to a carrier 35 slidably mounted in the drawer bottom, and provided at its rear 50 side with a hinged connected support 36 whose

lower end is provided with an opening to receive a guide card locking rod 10. This support is guided in the opening 37 of the carrier so that its lower end 38 may engage with the locking shoulders 39 formed in the bottom wall 4a of the drawer 5 bottom channel.

As will be noted from the figure of the drawings, the locking shoulders 39 for the greater part of the length of the drawer channel lie in the same plane. However, as the channel approaches the 10 end of the drawer the bottom wall 4b thereof is inclined upwardly which elevates the shoulders 39a above the plane of the shoulders 39, while the rear extremity of the channel 4b terminates in a flat supporting surface 40. With this arrangement, it will be apparent that as the follower 15 D is moved toward the rear end of the drawer, the plate 33 will tend to assume a more nearly vertical position. As previously indicated, the purpose of this construction is to straighten up the 20 plate 33 so that the drawer contents will not project over the upper edge of the back wall 3 of the drawer, and likewise the said plate will not project beyond the drawer. In this way the drawer contents and the follower plate 33 are both prevented from interfering with the rear wall x of the cabinet, and the filing contents of the space 25 of the drawer may be utilized to a maximum degree, while at the same time the drawer can readily move to its fully closed position within 30 the cabinet. It will also be apparent that the self-righting characteristic of the follower plate 33 contributes materially to the general compressive effect of the compressor C. The latter tends to force the drawer contents toward the rear wall 35 of the drawer, and except for the follower having the novel features referred to, the drawer contents would be thrown backwardly so as to interfere with closing the drawer to its fullest possible extent. Therefore, the follower plate 33 cooperates with the compressor device C to provide 40 both an efficient utilization of the filing contents space of the drawer and the proper functioning of the drawer, but the same style of follower may be used in file drawers not having 45 hinged or tilting fronts.

If desired a spring 41 may be used to connect the carrier 35 and the support 36 for the follower plate D. When the drawer is empty the 50 spring will tension the follower plate so that it will not fall forwardly when the drawer is pulled out with a jerk. On the other hand when the follower is backed up by the drawer contents, it will not be overbalanced by the movement of the 55

drawer. Therefore, the spring 41, or its equivalent, is an accessory which may be used under certain conditions.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

I claim:-

- 15 1. In a filing drawer having a bottom wall, provided with a channel whose bottom wall is inclined upwardly at its rear end, and a follower slidably in the drawer and including a plate, means for supporting the plate at a rearward inclination throughout the major portion of the length of the drawer, and a portion of said means adapted to engage the inclined bottom wall of the channel as it approaches the rear of the drawer, thereby tending to move the plate to a more nearly vertical position.
- 20 2. In a filing drawer having side, bottom and end walls, an adjustable rear follower mounted in the drawer, means for slidably mounting said follower to move in a horizontal plane, said follower including a hinged plate, means for supporting said hinged plate at an angle throughout the major portion of the length of the drawer, and means in the bottom of the drawer for engaging said supporting means for the plate to cause the latter to assume a more nearly vertical position as it reaches the end of the drawer, whereby the contents of the drawer will not project over and beyond the back wall of the drawer.
- 25 3. In a filing drawer having side, bottom and back walls, a rear follower slidably mounted in said drawer, said follower including a carrier member mounted for sliding movement in the drawer, keeper elements located beneath said carrier in the bottom of the drawer, a plate hinged to said carrier, a support for said plate having its lower end adapted to engage with said keeper elements on the bottom of the drawer, said keeper elements being arranged at a progressively inclined elevation as they approach the back wall of the drawer.

4. In a filing drawer, side bottom and back walls, a follower slidably in the drawer, said follower including a plate mounted for movement from an inclined to a vertical position, and cooperating means carried by the plate and the drawer bottom automatically to cause the plate to assume a substantially vertical position at the end of the drawer which will prevent the contents thereof from projecting beyond the back wall of the drawer.

5 5. In a filing drawer having a bottom wall formed in a horizontal plane and provided with a channel having its bottom wall provided with locking elements and inclined upwardly at its rear end, a follower including a sliding carrier movable along the drawer bottom, a plate pivoted to the carrier, and a support for the plate having its lower end operatively related to the locking elements and inclined portion of the channel.

10 6. In a filing drawer having a bottom wall, a space regulating follower slidable in the drawer, and cooperating means on the follower and on the bottom wall for moving the follower to a substantially vertical position as it approaches the rear of the drawer.

15 7. In a filing drawer having a bottom wall, a space regulating follower including a plate, means for normally supporting said plate in an inclined position, and means at the drawer bottom for engaging the said last named means for moving the follower plate to an upright position as it approaches the rear of the drawer.

20 8. In a filing drawer, a space regulating follower normally supported in an inclined position slidably mounted in the drawer, and cooperating means respectively on the follower and the drawer for automatically moving the follower to a vertical position as it approaches the rear of the drawer.

25 9. In a filing drawer having a bottom wall, a space regulating follower slidably mounted in the drawer, and cooperating means respectively on the follower and on the bottom wall for automatically maintaining a changed angular position of the follower with reference to the said bottom wall as the follower approaches the rear end of the drawer.

30 FREDERICK L. G. STRAUBEL.
